UNITED STATES PATENT OFFICE.

ALVAH M. GRIFFIN, OF KANSAS CITY, MISSOURI, ASSIGNOR TO J. L. JONES MANUFACTURING COMPANY, OF KANSAS CITY, MISSOURI, A CORPORATION OF LOUISIANA.

SILO.

1,145,306.

Specification of Letters Patent.

Patented July 6, 1915.

Application filed August 8, 1914. Serial No. 855,939.

To all whom it may concern:

Be it known that I, ALVAH M. GRIFFIN, a citizen of the United States, residing at Kansas City, in the county of Jackson and State of Missouri, have invented certain new and useful Improvements in Silos, of which the following is a specification.

This invention relates to wood stave silos and my primary objects are threefold, to produce a wood stave silo which will stand up against wind pressure as well as a barn or other outhouse; which cannot fall "to staves", and in which the staves are compelled through the expansion thereof, to return to normal relation after having been spaced apart more or less through shrinkage.

A further object is to produce a silo possessing the desirable qualities mentioned, which can be quickly and therefore cheaply erected by unskilled labor, and which is of light weight and hence can be shipped cheaply.

With these objects in view the invention consists in certain novel and peculiar features of construction and combinations of parts as hereinafter described and pointed out in the appended claims; and in order that it may be fully understood reference is to be had to the accompanying drawings, in which—

Figure 1, is a front elevation of a silo embodying my invention. Fig. 2, is a horizontal section on the line II—II of Fig. 1. Fig. 3, is an enlarged vertical section taken on the line III—III of Fig. 2. Fig. 4, is a section on the line IV—IV of Fig. 1. Fig. 5, is a section on the line V—V of Fig. 1. Fig. 6, is an enlarged section on the line VI—VI of Fig. 1. Fig. 7, is a sectional perspective view of a part of the silo.

In the said drawings, 1 is a rectangular frame, arranged horizontally and mounted upon four corner standards 2, and braced from said supports by braces 3. At one side the frame is provided with an opening 4, between the upper end of adjacent braces, and at the margins of the opening the adjacent side portions of the frame are secured to a pair of upright bars 5 constituting the sides of the door frame of the silo.

The horizontal frame is stiffened by corner braces 6 and the frame is anchored firmly to the ground by the fastening of its standards or legs to posts 7 embedded in the

ground and securely anchored by cross pieces 8 at their lower ends, it being understood that the pieces 8 should be buried several feet below the surface of the ground.

9 is an angle iron ring encircling the silo 60 and resting upon the rectangular frame, and overlapping and bolted or otherwise fastened at 9^a to the base or horizontal flange of said ring (see Fig. 1) are angle plates 10 bolted as at 11 to the anchorage frame. The 65 connection between the ring and angle plates and between the latter and the anchorage frame guards against the latter bulging outward by warpage or otherwise.

The silo proper is composed of staves 12, 70 tongued and grooved together, the staves being arranged to form almost a complete cylinder, and the two staves which are spaced apart are nailed or otherwise securely fastened to the door frame bars 5, as 75 will be readily understood by reference to Figs. 2 and 6, the staves being fitted against the inner side of the ring 9.

The horizontal flange of the angle ring at a suitable distance from each end thereof, is 80 cut off and the ends of said flange are then bent up to form stops or shoulders 13 adapted under sufficient contraction of the silo to abut against the outer edges of the bars 5 and thus tend to limit such contracting action. The ends of the vertical flange of said ring terminate in outwardly bent stops or shoulders 14 adapted under sufficient expansion of the silo to abut against the inner edges of the said bars. The space between 90 said shoulders therefore represents the lateral displacement or movement that is possible for the interposed bar 5 to have under the expansive and contractive actions of the silo.

In order that the staves which are fastened as hereinbefore mentioned to bars 5, may fit flatly against the same for their full length so as to make the silo airtight at such points, the bars 5 are provided with transverse grooves 15 of sufficient depth to just accommodate the vertical flange portions of the ring between the stops or shoulders 13 and 14 thereof, as will be seen by reference to Figs. 6 and 7. If desired the upturned 105 stops or shoulders 13 may be braced by triangular braces 16, as the staves are practically suspended up on the angle iron ring 9, all except the two fastened to the bars 5 being provided with a down-turned clip 110

- or saddle plate 17, which fits slidingly upon and over the vertical flange of the said ring as shown in Figs. 1 and 3 most clearly, it being understood of course that a silo erected as described and largely suspended upon the ring needs no special foundation or special leveling of ground, it being made airtight at the bottom if desired by banking up loose earth against it.
- 10 Fitting at suitable intervals between and fastened to the bars 5 are horizontal cross pieces 18, which form effective braces against approaching movement of said bars, spreading or receding movement of the bars being prevented by cross rods 19 which extend through the bars 5, and are engaged at their extremities by nuts 20. The cross bars 18 serve as supports for brackets 21 which constitute rungs of a ladder to enable one to climb the silo.

Where the silo is of such height that it is necessary to use two or more staves fitted together endwise, as is usually the case, I preferably provide the abutting ends of the staves with bifurcations 22 for the reception of the ends of plates 23 which correspond substantially with the width of the staves and bridge the joint between abutting ends as indicated in Fig. 5. By this construction it is not necessary to employ any metal on the inside of the silo.

Coöperating with what I term the suspension ring, are two additional rings 24, one below and the other above the central ring. These rings are preferably in the form of split rings. They encircle the silo and their ends extend slidingly through bars 5, the connection with the staves being by virtue of a series of tubular clips 25 through 40 which the rings extend slidingly, provided with flat bases 26 through which screws or equivalent devices extend to fasten the clips to the staves.

As thus far described it will be seen that the staves are practically free in contracting to separate along their side edges but that upon reexpanding they will resume their original relation and produce tight joints along their side edges, the bands obviously holding them in vertical position.

To guard against unrestrained expansion and to coöperate with the three rings in maintaining the staves vertical and to materially assist in preventing the staves from buckling outward or twisting between said rings, a series of wire cable hoops 27 tightly encircle the staves and are secured at their ends to eye bolts 28, which extend through the bars 5 and are engaged at the inner sides 55 of the latter by nuts 29, the hoops being prevented from slipping up and down by tubular clips 30, secured to an occasional stave, said clips being the same structurally as the clips 25. Preferably the ends of the hoops 60 are looped through the eyes of the bolts 28,

and clamps 31 are employed to adjustably secure the hoops against slippage, so that the hoops can be used to take up any undue shrinkage which may occur during an excessive long hot season when the silo is 70 empty. Of course if the silo is full there will be no shrinkage or expansion which will not be accommodated automatically by the floating action of the staves upon the suspension band and the two coöperating 75 bands.

The connections between the ring 9 and the angle plates 10 guard against any possibility of the sides of the angular frame 1 warping outwardly and thereby withdrawing the support of the frame from under the ring, it being equally obvious that through such connection shrinkage of the silo must be attended by shrinkage or inward bowing of the sides of said frame so that whatever 25 the condition of the silo the ring will always remain supported by the anchorage frame and hence through its connection with the clips 17, will guard against collapse of the silo or the falling in of the staves 90 thereof.

From the above description it will be apparent that I have produced a silo embodying the features of advantage enumerated as desirable, and I wish it to be understood 95 that while I have illustrated and described what I now deem the preferred embodiment of the same I reserve the right to make all changes falling within the spirit and scope of the appended claims.

I claim:

1. In a silo a cylindrical body embodying vertical staves fitting edgewise together and provided externally with saddle clips, and a broken ring snugly embracing the silo and 105 bearing a slidable relation thereto and fitting under and forming a support for the said saddle clips and means for supporting said broken ring.

2. In a silo, a cylindrical body embodying vertical staves fitting edgewise together and provided externally with saddle clips, a broken ring snugly embracing the silo and bearing a slidable relation thereto and fitting under and forming a support for the 115 said saddle clips and means for supporting said broken ring; in combination with a plurality of auxiliary broken rings embracing the silo above and below the first-named ring and slidably connected to the silo to 120 permit the same to expand and contract freely.

3. In a silo, a cylindrical body embodying vertical staves fitting edgewise together and provided externally with saddle clips, a 125 broken ring snugly embracing the silo and bearing a slidable relation thereto and fitting under and forming a support for the said saddle clips and means for supporting said broken rings; in combination with a 130

plurality of auxiliary broken rings embracing the silo above and below the first-named ring and slidably connected to the silo to permit the same to expand and contract freely, certain of the staves having tubular clips fitting sliding on said auxiliary rings.

4. In a silo, a cylindrical body embodying vertical staves arranged edgewise together and a pair of vertical bars spaced apart, means for holding the bars in rigid relation to each other and the adjacent staves, a suitable support, a broken ring carried by said support and snugly embracing the silo and bearing a sliding relation near its extremities to the said bars, and means for slidably supporting the silo on said ring.

5. In a silo, a cylindrical body embodying vertical staves fitting edgewise together and provided externally with saddle clips, a broken ring snugly embracing the silo and bearing a sliding relation thereto and fitting under and forming a support for the said saddle clips and means for supporting said broken ring; in combination with a plurality of auxiliary broken rings embracing the silo above and below the first-named ring, and slidably connected to individual staves of the silo externally of the latter and preventing twisting or warping of the staves without interfering with lateral expansion and contraction thereof.

6. In a silo a cylindrical body embodying vertical staves arranged edgewise together, a pair of vertical bars spaced apart and rigidly secured to two of the staves, means for holding the bars in rigid relation to each other, a plurality of hoops embracing the silo and secured to said bars, a suitably supported broken ring embracing the silo and bearing a sliding relation to said bars, saddle clips secured to certain of the staves and fitting slidably over and upon said ring, a pair of broken rings embracing the silo above and below the first-named ring and bearing a sliding relation to the vertical bars, and clips secured to certain of the staves and fitting slidably on the said pair of rings.

7. In a silo, a cylindrical body, embodying vertical staves fitting edgewise together and provided externally with saddle clips, a pair of vertical bars spaced apart and secured to two of said staves, means for holding the bars in rigid relation to each other, a broken ring embracing the silo and bearing a sliding relation to said bars and provided inward and outward of the latter with shoulders for abutment against the said bars to limit expansion and contraction of the silo, and fitting slidably under the said saddle

clips as a support for the staves equipped therewith and means for supporting the said broken ring.

8. In a silo an anchorage comprising standards, a horizontal frame mounted upon the standards, a broken ring carried by said frame, a cylindrical body fitting snugly in the frame and composed of a pair of vertical bars spaced apart and a plurality of vertical staves fitting edgewise together, the bars fitting slidably on said ring and certain of said staves having saddle clips resting on and fitting down over said ring, and provided above and below the ring with clips, and broken rings extending slidably through said clips and slidably secured to said bars.

9. In a silo, an anchorage comprising standards, a horizontal frame mounted upon the standards, a broken ring carried by said frame, a cylindrical body fitting snugly in the frame, and composed of a pair of vertical bars spaced apart and a plurality of vertical staves fitting edgewise together, the bars fitting slidably on said ring and certain of said staves having saddle clips resting on and fitting down over said ring, and provided above and below the ring with clips, broken rings extending slidably through said clips and slidably secured to said bars, means for securing the bars in rigid relation, and hoops embracing the silo and connected to said bars to prevent undue expansion of the silo.

10. In a silo, an anchorage comprising standards, a horizontal frame mounted upon the standards, a broken ring carried by said frame, a cylindrical body fitting snugly in the frame, and composed of a pair of vertical bars spaced apart and a plurality of vertical staves fitting edgewise together, the bars fitting slidably on said ring and certain of said staves having saddle clips resting on and fitting down over said ring, and provided above and below the ring with clips, broken rings extending slidably through said clips and slidably secured to said bars, means for securing the bars in rigid relation, hoops embracing the silo and connected to said bars to prevent undue expansion of the silo, the first-named ring being provided at each end with a pair of shoulders adapted to limit or check expanding and contracting or shrinking of the silo.

In testimony whereof, I affix my signature, in the presence of two witnesses.

ALVAH M. GRIFFIN.
